CLAIM

The ornamental design for a lug for a muzzle device, as shown and described.

DESCRIPTION

FIG. 1 is a front perspective view of the lug for a muzzle device;

FIG. 2 is a rear perspective view thereof;

FIG. 3 is a front elevation view of thereof;

FIG. 4 is a rear elevation view of thereof;

FIG. 5 is a left side elevational view thereof, the right side being a mirror image; and,

FIG. 6 is a top plan view thereof, the bottom plan view being a mirror image.

The broken lines are used to illustrate unclaimed portions and form no part of the claimed design.

1 Claim, 3 Drawing Sheets---
